SLIDING CHEEK PIECE FOR GUNS

Elmer E. Miller and Howard L. Miller, Millersburg, Pa.

Application August 18, 1936, Serial No. 96,678

5 Claims. (Cl. 42—71)

This invention relates to guns and particularly to gun stocks.

In aiming and firing a gun, particularly in trap shooting, it is most desirable in order to secure quick and accurate shooting, that the gunner lay his cheek against the stock, so that his eye may be brought into proper position for sighting the piece. Upon the recoil of the gun, however, the stock jumps rearward and slides against the face of the gunner. Continued shooting in this manner irritates and chafes the skin of the face and also tends to bruise the muscles of the cheek. This is particularly true where a large number of shots are fired from the gun. As a consequence, gunners may become gun-shy and there is an instinctive impulse to lift the cheek from the gun stock just as the trigger is pulled. No matter how slight this lift is, there is likelihood of inaccurate shooting.

20 The object of the present invention is to eliminate this by the provision of a cheek rest or piece which extends down over the side face of the stock nearly to the lower edge thereof and which is slidably mounted on the stock for longitudinal movement relative thereto, the cheek piece being yieldably held in a normal position by a spring. When the gun recoils, the stock jumps rearward relative to the cheek piece and then moves forward relative thereto on the rebound of the gun.

25 Inasmuch as the cheek piece or rest is stationary, it does away with any chafing friction between the gun and stock and the cheek, or with any tendency to bruise the cheek muscles or render them sore.

30 Our invention is illustrated in the accompanying drawing wherein:

Figure 1 is an elevation of a gun stock with our cheek piece applied thereto, showing the slide for the cheek piece in dotted lines;

35 Figure 2 is a section on the line 2—2 of Figure 1;

Figure 3 is a longitudinal section on the line 3—3 of Figure 1;

40 Figure 4 is a side elevation of the guide frame and sliding plate.

45 Referring to this drawing, 10 designates the stock of the gun which may be of any suitable construction and may, of course, be the stock of any form of gun. This stock is cut away to provide a slot 11 extending longitudinally of the stock. Disposed within the slot is a guide frame 12 which in turn is longitudinally slotted at 13.

50 The recess or slot 11 of the stock is undercut at one end at 14, and the guide frame at this end 55 is beveled to fit beneath this undercut end of the

slot. The opposite end of the guide frame is perpendicular to the surface of the stock and a screw 15 extends through the rear of the stock and engages the adjacent end of the frame holding it in place.

5 Disposed against the outer face of the gun stock, that is the lateral face of the stock against which the gunner lays his cheek is the cheek rest or cheek piece designated 16. This has a length greater than the length of the slot 11 and is approximately T-shaped in cross-section, as shown in Figure 2, to provide a portion 17 which extends into the longitudinal slot of the guide 12. This portion which extends down into this slot is, of course, shorter than the slot in the guide frame. 10 The cheek rest preferably extends over the upper edge face of the stock but must extend downward over the side face of the stock nearly to the lower edge thereof. This cheek rest terminates short of the butt of the gun so that it in no way 15 affects the abutment of the stock against the shoulder and does not in any way act as a recoil pad.

15 Attached to the inner face of the portion 17 is a metallic plate 18 which has a width equal to 20 the width of the guide frame and has a length equal to the length of the portion 17. The extremities of this metal plate 18 are inwardly bent, as at 19, to bear against the ends of the portion 17. The portions 19 are only wide enough 25 to fit within the slot 13, but the ends of the flat portion of the plate 18 on each side of these inwardly bent portions 19 are slightly bent inward, as at 20. These inwardly bent extremities 30 ride against the outer face of the guide frame 35 12 and thus the body of the plate 18 is slightly spaced from the outer face of the guide frame, thus reducing friction. The plate 18 is held by screws 21 or other means of any suitable character 40 to the cheek piece or rest 16.

45 A coiled contractile spring 22 is attached at one end to a pin 23 extending outward from one end of the guide frame and at its other end, the spring is attached to the extremity of the plate 18, thus this spring tends to hold the slide of the 50 cheek piece at the rear end of the slot 13. When the gun is fired, the recoil carries the stock rearward and with it carries the frame 12, while the cheek piece and the plate 18 remain stationary. As soon as the recoil has been expended and the 55 gun rebounds, the cheek piece returns to its initial position.

We have illustrated the butt of the stock as being provided with recoil pads 24 which overlie the end of the screw 15, these recoil pads being,

of course, detachably held to the stop. This is purely illustrative and has nothing to do with our particular invention.

While we have illustrated a form of this invention which has been found to be thoroughly effective in actual practice, we do not wish to be limited to the particular details as obviously, these might be varied in many ways without departing from the spirit of the invention as defined in the appended claims.

What we claim is:

1. In a gun stock, a longitudinally extending, slotted guide frame inserted within the side wall of the gun stock, a cheek rest disposed upon and extending down over the side face of the gun stock and having a portion thereof extending into said slot of the guide frame, this portion being shorter than the slot, a plate bearing against the inner face of the guide frame and having sliding engagement therewith and attached to the inwardly extending portion of the cheek rest, and a spring attached at one end to the inner face of the guide frame and at the other end to one end of said plate and urging 25 the plate and the cheek rest rearward.

2. A gun stock having a longitudinally extending recess in its side wall, the recess being undercut at one end, a longitudinally slotted guide frame disposed in said recess and having a 30 beveled end fitting beneath the undercut end of the recess, a screw extending through the butt of the stock and engaging the adjacent end of the guide frame to thus hold the guide frame in place, a cheek rest slidably mounted upon the 35 outer face of the guide frame and fitting against the adjacent side face of the gun stock, a plate disposed on the inner face of the guide frame, a connection between the plate and the cheek rest, and a contractile spring attached at one end 40 to the rear end of the guide frame and at its other end to the forward end of the plate and

acting to retract the plate and the cheek rest toward the butt of the stop.

3. A gun stock having a longitudinally extending recess on one side face, a longitudinally slotted guide frame disposed in said recess, a 5 cheek rest fitting against one side of the stock and having a portion extending into said slot of the guide frame, said portion being less in length than the slot of the guide frame, a plate extending longitudinally of the guide frame on the inner face thereof and attached to said cheek rest through the slot in the guide frame, said plate having inwardly turned extremities bearing against the end portion of the cheek rest which extends into the guide frame, said plate on each 15 side of said inwardly extending portion being inwardly turned to bear against the adjacent face of the guide frame, and a spring urging said plate and the cheek rest rearward in the slot.

4. A gun stock, a cheek rest having a portion 20 slidably engaging the upper face of the stock and a portion extending down over the side face of the stock nearly to the lower edge thereof, the cheek rest being slidably mounted upon the side face of the stock, and a spring urging the 25 cheek rest rearward toward the butt of the gun, the cheek rest terminating short of the butt of the gun.

5. A gun stock having on one lateral face a longitudinally extending recess, a cheek rest extending downward from the upper face of the stock nearly to the lower edge face thereof and contacting with the side face of the stock, the cheek rest having a portion extending into said recess but less in length than the length of the 35 recess, means holding the inwardly projecting portion of the cheek rest in sliding engagement with the stock, and a spring urging the cheek rest rearward within the recess.
